UNITED STATES PATENT OFFICE.

WALTER O. SNELLING, OF PITTSBURGH, PENNSYLVANIA, ASSIGNOR OF FIFTY-ONE
ONE-HUNDREDTHS TO JOHN T. MILLIKEN, OF ST. LOUIS, MISSOURI.

PROCESS OF PURIFYING OILS.

1,215,732.

Specification of Letters Patent. Patented Feb. 13, 1917.

No Drawing.

Application filed April 8, 1915. Serial No. 19,864.

To all whom it may concern:

Be it known that I, WALTER O. SNELLING, a citizen of the United States, residing at Pittsburgh, in the county of Allegheny and

5 State of Pennsylvania, have invented certain new and useful Improvements in Processes of Purifying Oils, of which the following is a specification.

This invention relates to processes of purifying oils; and it comprises a process of removing sulfur from oils wherein crude oils, or distillates therefrom, containing sulfur are heated or distilled in the presence of cracked hydrocarbons having an affinity 10 for sulfur; all as more fully hereinafter set forth and as claimed.

Many crude petroleums contain sulfur and this sulfur is apt to occur in volatilizable compounds which will distil over with distillates, contaminating the same and rendering necessary the use of expensive purifying treatments. The presence of sulfur in such products as gasoline or kerosene is highly undesirable for many reasons. The form 20 in which the sulfur occurs in these oils is not definitely known but it appears to occur as what is sometimes known as "sulfid sulfur"; in a state of combination analogous to its state of combination in such compounds as ethyl sulfid. Very many ways of removing the sulfur have been proposed, such as the use of copper oxid, lead compounds, etc.; but these methods all require the use of chemicals which are expensive, or 30 which necessitate an expensive regeneration; or both.

I have found however that this sulfur occurring in this state of combination may be readily transferred from one hydrocarbon to another; and that its tendency to unite to and firmness of combination with, heavy hydrocarbons is greater than its tendency to unite to, and firmness of combination with, lighter hydrocarbons. This enables me, so to speak, to transfer the sulfur from the more valuable light and relatively volatile hydrocarbons such as gasoline and kerosene to the less valuable heavy and relatively less volatile hydrocarbons. I have 40 found, for example, that by heating a gasoline or a kerosene containing sulfur together with a heavy cracked oil of high boiling point, the sulfur is transferred from the gasoline or from the kerosene, to the heavy

hydrocarbon, and the gasoline or kerosene, 55 can then be easily separated from the sulfur-containing high boiling oil by simple distillation. The distillate so obtained is free, or substantially free, from sulfur. The theory of this reaction appears to be that the sulfur has greater affinity for the more complex heavy hydrocarbons than it has for the lighter, less complex hydrocarbons, so that in the heating operation it passes from the one to the other. The same treatment 60 may be applied to a crude oil, as by mixing a sulfur-containing crude oil with a heavy cracked hydrocarbon of, say, the boiling point of gas oil, solar oil, lubricating oil, wax oil and performing the distillation in 65 the usual manner. Cracked or tarry still residues which are not valuable except for fuel may be used for the present purposes. The gasoline or kerosene components of the crude oil will distil over substantially free 70 of sulfur. The sulfur remains in the residual high boiling oil, whence it may be removed; or the residual high boiling oil may be used for fuel or other purposes where the presence of sulfur is unimportant. Or 75 the residual oil containing the sulfur may be submitted to a cracking distillation to give cracked gasoline and cracked kerosene. The cracked residue is capable of absorbing still more sulfur from another portion of 80 oil.

The power of abstracting sulfur from the natural sulfur compounds in crude petroleum and its low boiling distillates appears to be one which is common to all cracked 85 petroleum products; a cracked gasoline, for example, having the power of absorbing sulfur from a natural distillate containing sulfur. But for obvious reasons, it is better to perform the abstraction of sulfur 90 with a high boiling hydrocarbon product from which the material to be purified can be afterward separated by simple distillation.

The cracked high boiling hydrocarbons, 100 which may advantageously be such as have a boiling point above 500° F., may be obtained in any convenient manner, as by using the residue from an ordinary cracking distillation. But it is better to make the 105 sulfur-absorbing material in a special way, as by cracking under reduced pressure. For example, oil and oil vapors may be led

through a pyrolyzing zone, such as a hottube, under reduced pressure. For example, crude petroleum, gas oil, etc., may be transmitted through a tube heated to, say, 500° to 600° 5 F. and thence through a cooler or condenser. This results in a liquid containing cracked gasoline, or cracked kerosene, and cracked high boiling oils. On distillation of this product, the gasoline will come over 10 substantially free of sulfur; the sulfur if any be present, remaining with the high boiling residue in the still.

This cracked high boiling residue may next be mixed with crude petroleum of the 15 same or another kind and distillation resorted to in the usual manner until the gasoline and kerosene are distilled off. The distillation may be carried further to form high boiling lubricating oil, such as spindle 20 oil, the grades known as "solvent oils", etc. The residue in the still may next be submitted to a cracking operation and the product obtained used as before.

Or, and advantageously, gasoline or kerosene or spindle oil may be redistilled in the 25 ordinary way after admixing with the high boiling cracked oil and heating together. This heating may be under a reflux condenser for a time in the case of oils whose 30 sulfur is difficult to transfer; or it may be heating merely in the manner incident to redistilling and regaining the gasoline or kerosene which has been mixed with the high boiling oil. Heating the two oils (the 35 cracked oil and the oil from which sulfur is to be abstracted) may be advantageously performed under pressure.

Ordinarily the high boiling oil which has been used in any of these ways and is, so to 40 speak, saturated with sulfur is finally burned under the boilers or stills or is sent into the market as fuel oil.

What I claim is:

1. The process of removing sulfur from hydrocarbon oils which comprises heating 45 a sulfur containing oil in the presence of a cracked oil capable of absorbing sulfur.

2. The process of removing sulfur from hydrocarbon oils which comprises distilling such an oil in the presence of a heavy 50 cracked oil capable of absorbing sulfur.

3. The process of removing sulfur from low boiling petroleum oils which comprises heating such a low boiling oil in the presence of a heavy cracked oil capable of absorbing 55 sulfur.

4. The process of removing sulfur from low boiling petroleum oils which comprises distilling such a low boiling oil in the presence of a heavy cracked oil capable of absorbing 60 sulfur.

5. The process of removing sulfur from low boiling petroleum oils which comprises mixing a crude petroleum with a cracked high boiling oil capable of absorbing sulfur 65 and heating them together.

6. The process of removing sulfur from low boiling petroleum oils which comprises mixing a crude petroleum with a cracked high boiling oil capable of absorbing sulfur 70 and then distilling off the low boiling oils.

7. The process of removing sulfur from low boiling petroleum oils which comprises mixing a crude petroleum with a cracked high boiling oil capable of absorbing sulfur 75, heating this mixture under pressure, to facilitate interchange of the sulfur from the low boiling hydrocarbons to the cracked, high boiling oils, and then distilling off the low boiling oils.

In testimony whereof, I affix my signature.

WALTER O. SNELLING.
